UNITED STATES PATENT OFFICE.

JAMES W. VAN METER, OF SAN FRANCISCO, CALIFORNIA.

PERCUSSION APPARATUS.

Application filed January 14, 1920. Serial No. 351,318.

To all whom it may concern:

Be it known that I, JAMES W. VAN METER, a citizen of the United States, residing at San Francisco, in the county of San Francisco and State of California, have invented new and useful Improvements in Percussion Apparatus, of which the following is a specification.

My invention relates to percussion devices 10 wherein an upward blow is delivered in contradistinction to the usual downward blow of trip hammers and other well known percussion devices. The present device may be used for a variety of purposes by changing 15 the form of the piston and anvil. It is particularly advantageous for stamping ores, metal, and the like.

The present form of the device is that of a cylinder and piston wherein an explosive 20 charge is made use of to drive the piston upward against an anvil. Two chambers are made use of, one receiving the explosive charge to drive the piston and the other serving as a counterbalancing and cushioning 25 chamber for the heavy piston. I employ air under pressure to obtain the necessary compression of the charge of explosive mixture in the working chamber, and after the charge is exploded, the force of the blow is 30 augmented by admitting compressed air to the second chamber, such air being also used to cushion the weight of the piston in its downward stroke. While the present device is shown as being operated by an explosive 35 mixture, I do not limit myself to that form of operation, and desire to point out that steam, compressed air, or any other suitable agent may be used to drive the piston.

In the accompanying drawings:—
40 Fig. 1 shows a vertical central sectional view of a device embodying my invention.

Fig. 2 shows a similar view partly in elevation.

Fig. 3 shows a side elevation of the device 45 partly in section.

The device as here shown comprises an upright frame 10 resting on a base 11. The frame 10 is provided at its upper end with a cylinder 12 having a large and small bore 50 within for the purpose of receiving a double piston 13 and 14. The upper bore is used as a cushioning and counterbalancing chamber and the lower bore is used as an explosive chamber. The upper extremity of the frame 55 10 is fitted with two upright members 15 on which rests a crosshead or anvil 16 secured

to the uprights by nuts 17. This anvil or crosshead receives the blow from the head of the piston 13.

The frame 10 is held in position on the 60 base 11 by means of a system of supporting rods 18 which form a tripod. A projecting rim 19 on the bottom of the frame 10 carries a rubber buffer 20 resting against a circular ring 21, which latter is secured to the 65 base 11 by means of bolts 22. The legs of the tripod have their upper ends fitting loosely into sockets in the frame 10 and at their lower ends are screwed into nuts 23, which latter rest on rubber cushions 24 seated in cups 25 on the base 11. The purpose of this construction is to lift the frame 10 and hold it closely against the rubber buffer 20. The weight of the frame normally rests on the legs 18 and these in turn rest on the 70 base through the cushions 24. The shock caused by the upward blow of the piston will be taken up by the buffer 20 and the jar, if any, resulting from the descending piston will be received by the cushions 24. 80

The pistons 13 and 14 are provided with rings 26 and 27 whereby to form a tight sliding fit with the walls of the surrounding cylinders. The bottom of the upper cylinder is fitted with a rubber disk 28 to form 85 a cushion for the descending piston. An air-passage 29 is formed in the wall of the upper cylinder and is fitted with a check-valve 30 opening outwardly, said valve being maintained in closed position by means 90 of an adjustable spring. A pipe 31 forms a communication between the air-passage 29 and an air reservoir 32. A circular recess 33 extends entirely around the wall of the upper cylinder and a series of ports 34 opening 95 into the interior of the cylinder. This annular passageway is in communication also with the air reservoir 32 through the pipe 31.

The lower chamber is provided with a piston valve 35 actuated by a handle 36, said valve serving to control the admission of compressed air to the lower cylinder. Air under pressure is supplied from a tank 37 through a valved pipe 38 and ports 39. Liquid fuel is admitted with the compressed air by means of a small pump 40 in the bottom of the frame 10, said pump being actuated by an extension 41 on the end of the handle 36. The liquid fuel is supplied to the pump 40 through a pipe 42. The explosive mixture, after entering the lower chamber, is ignited 105 110

by means of a spark plug 43, the circuit through which is closed by means of a vertical rod 44 in the lower end of the upper cylinder, said rod being normally pressed 5 upwardly by a spring and being positioned to move downwardly when the upper piston reaches the bottom of its cylinder. With the upper piston at the bottom of its cylinder, the rod 44 will be moved downwardly to break the circuit, but when the piston is moved upwardly some distance, the rod 44 will rise under pressure of the spring to close the circuit, thereby serving as a timer for igniting the charge in the lower 10 chamber. A check-valve 45 is fitted in the 15 side of the upper cylinder and opens inwardly, serving to admit air to the upper chamber when an excess of vacuum is present therein.

20 In the operation of the device herein shown and described, a charge of liquid fuel is forced by the pump 40 into the chamber of the piston valve 35 and is in turn picked up by means of the compressed air and 25 carried into the lower chamber. The lower piston will start to rise when sufficient pressure has been accumulated within the combustion chamber to counterbalance the weight of the piston. However, the piston is 30 restrained against upward movement by reason of a tendency to form a vacuum in the upper cylinder. When the upper piston reaches the line designated AB, the timer 44 will close the circuit to ignite the explosive 35 charge whereupon the upper piston will uncover the ports 34 admitting compressed air from the reservoir 32 which will augment the force of the explosion and drive the piston upwardly against the anvil.

40 The blow having been struck, the handle 36 is lifted to uncover the port in the lower end of the lower chamber to the atmosphere and allow the burned gases to escape through the open end 35^a of the sleeve of the piston 45 valve 35. It should be understood that the pressure of air in the upper chamber is maintained at a point slightly below what is required to support the heavy piston, and therefore the piston will slowly descend once 50 the force of the explosive mixture has been dispelled. The air in the upper chamber is forced back into the reservoir 32, first through the ports 34 until they have been covered and thereafter through the check 55 valve 30, allowing the piston to gradually and slowly settle to the bottom of the cylinder where it will rest upon the rubber disk 28. The reservoir 32 is shown as being supplied with or through a valved pipe 32^a from 60 the reservoir 37, and it has a safety valve 32^b to maintain the pressure at the desired point. In the initial stage of operation of the piston, should the vacuum in the upper chamber become too great to allow the piston to rise to 65 a point where the timer 44 is set off, then

the check valve 45 will open to admit air from the outside.

Among the many advantages of my apparatus is that I accumulate the necessary pressure in the working cylinder by utilizing the weight of the piston and a slight vacuum or suction in the upper chamber which tends to restrain the upward movement of the piston until the ports 34 are uncovered. Also, after the explosive charge has been 70 fired, and the piston 13 uncovers the ports 34, there is an inrush of air under pressure from the reservoir 32 which will assist the upward movement of the piston, such air remaining to cushion the descent of the piston. The speed of descent of the piston can be accurately controlled, and upon reaching its lowermost limit, it is cushioned by the rubber mat 28. Also of advantage in the 75 construction of this apparatus is the rubber 80 ring 20 for cushioning the frame when the blow is struck and the rubber blocks 24 take up any shocks incident to the return of the piston.

85 Various changes in the construction and arrangement of the several parts may be employed without departing from the spirit of my invention as disclosed in the appended claims.

90 The presence of the rubber mat 20 in the bottom of the upper chamber insures a complete expulsion of all air pressure from the chamber when the piston reaches the bottom of the cylinder. Therefore, on the initial 95 up stroke of the piston 13, there is certain 100 to be the necessary vacuum or suction to restrain the piston.

Having thus described my invention, what I claim and desire to secure by Letters Patent 105

1. A percussion apparatus comprising a cylinder, and piston, means for admitting an explosive mixture under pressure at one end of the cylinder, means for retarding the movement of said piston while the explosive mixture is being admitted, and means for exploding said mixture when the piston has moved a predetermined degree under the influence of the explosive mixture under pressure.

110 2. A percussion apparatus comprising a superposed anvil, an upwardly moving piston to co-operate therewith, means for admitting explosive fluid to drive said piston, and a counterbalancing means operative on the upward movement of the piston to assist in lifting the latter and effective on the return stroke to cushion the downward movement of the piston.

115 3. A percussion apparatus comprising a cylinder, and piston, means for admitting an explosive mixture under pressure at one end of the cylinder, means for retarding the movement of said piston while the explosive mixture is being admitted, means for ex- 120 125 130

ploding said mixture when the piston has moved a predetermined degree under the influence of the explosive mixture under pressure, and means for admitting air under pressure after said explosion, said air being adapted to aid in advancing the piston.

4. A percussion apparatus comprising a superposed anvil, an upwardly moving piston to co-operate therewith, a working chamber for explosive fluid to drive the said piston upwardly against the anvil and a second chamber for expansive fluid to assist in lifting the piston on the upward stroke and effective to cushion the return stroke of said piston.

5. A percussion apparatus comprising a superposed anvil, an upwardly moving piston to co-operate therewith, a working chamber for explosive fluid to drive the said piston upwardly against the anvil and a second chamber for expansive fluid to assist in lifting the piston on the upward stroke and effective to cushion the return stroke of said piston, said second chamber being below atmospheric pressure until the explosive charge is ignited, whereby to restrain upward movement of the piston and permit compression of the explosive charge in the working chamber.

30 6. A percussion apparatus comprising a double piston and cylinder forming two chambers, one for explosive mixture and the other for expansive fluid co-operating to drive the piston upwardly forcefully and to cushion the descent of the piston.

7. A percussion apparatus comprising a double piston and cylinder forming two chambers, one for explosive mixture and the other for expansive fluid co-operating to 40 drive the piston upwardly forcefully and to cushion the descent of the piston, said second chamber being normally below atmospheric pressure until the explosive charge is ignited, and thereafter open to admit compressed air to assist in lifting the piston.

8. A percussion apparatus comprising a double piston and cylinder forming two chambers, one for explosive mixture and the other for expansive fluid co-operating to 50 drive the piston upwardly forcefully and to cushion the descent of the piston, said second chamber being normally below atmospheric pressure until the explosive charge is ignited and thereafter open to admit compressed air to assist in lifting the piston, the compressed air in said second chamber being slightly less than required to support the

weight of the piston whereby when the force of the exploded gases has been dispelled the piston will be allowed to descend 60 against the pressure of air in the second chamber.

9. A percussion apparatus comprising a double piston and cylinder forming two chambers, one chamber for explosive mixture and the other for an expansive fluid, and a timer for the explosive mixture releasable when the piston reaches a predetermined point in its upward travel.

10. A percussion apparatus comprising a base, a cylinder and piston mounted vertically therein, a superposed anvil against which one end of the piston is adapted to strike, means for admitting explosive mixture in said cylinder adjacent the other end 75 of the piston whereby with the explosion thereof the piston will be impelled against the anvil, and means interposed between the base and cylinder adapted to cushion the force of the upward blow delivered by the piston 80 to the anvil, and to likewise cushion the shock of the returning piston.

11. A percussion apparatus comprising a cylinder, a piston therein, a combined pump and valve mechanism for admitting an explosive mixture under pressure at one end 85 of the cylinder, means for retarding the movement of said piston while the explosive mixture is being admitted, and means for exploding said mixture when the piston has 90 moved a predetermined degree under the influence of the explosive mixture under pressure.

12. A percussion apparatus comprising a double piston, separate chambers therefor, 95 one receiving an explosive charge to drive the piston upwardly and the other acting initially by vacuum to restrain the upward movement of the piston, and afterwards receiving an expansive fluid to counterbalance 100 and cushion the piston, and a compressible mat in the bottom of the last named chamber to insure a seat for the piston and obtain a complete expulsion of expansive fluid from the piston chamber when said piston 105 completes its downward stroke.

In testimony whereof I have hereunto set my hand in the presence of two subscribing witnesses.
